DESIGN FOR A HEAT TREATING APPARATUS FOR HARDENING METAL PIECES

Thomas A. Waltz, Cincinnati, Ohio

Application November 14, 1944, Serial No. 116,328

Term of patent 7 years

(Cl. D49—1)

To all whom it may concern:

Be it known that I, Thomas A. Waltz, a citizen of the United States, residing at Cincinnati, in the county of Hamilton and State of Ohio, have invented a new, original, and ornamental Design for a Heat Treating Apparatus for Hardening Metal Pieces, of which the following is a specification, reference being had to the accompanying drawing, forming a part thereof.

The figure is a perspective view of a heat treating apparatus for hardening metal pieces, illustrating my new design. The design will appear the same if viewed from either side.

I claim:

The ornamental design for a heat treating apparatus for hardening metal pieces, substantially as shown and described.

THOMAS A. WALTZ.
